(57) **CLAIM**

The ornamental design for an adjustable luminaire, as shown and described.

DESCRIPTION

FIG. 1 is a bottom view of an adjustable luminaire in a closed position, showing a first variant of the design, and a top view thereof is a mirror image;

FIG. 2 is a front view thereof, and a rear view thereof is a mirror image;

FIG. 3 is a right-side view thereof, and a left-side view thereof is a mirror image;

FIG. 4 is a top perspective view thereof;

FIG. 5 is a bottom view thereof in a half-open position;

FIG. 6 is a bottom view thereof in an open position;

FIG. 7 is a bottom view of an adjustable luminaire in a closed position, showing a second variant of the design, and a top view thereof is a mirror image;

FIG. 8 is a front view thereof, and a rear view thereof is a mirror image;

FIG. 9 is a right-side view thereof, and a left-side view thereof is a mirror image;

FIG. 10 is a top perspective view thereof;

FIG. 11 is a bottom view thereof in a half-open position;

FIG. 12 is a bottom view thereof in an open position;

FIG. 13 is a bottom view of an adjustable luminaire in a closed position, showing a third variant of the design, and a top view thereof is a mirror image;

FIG. 14 is a front view thereof, a rear view thereof is a mirror image;

FIG. 15 is a right-side view thereof, and a left-side view thereof is a mirror image;

FIG. 16 is a top perspective view thereof;

FIG. 17 is a bottom view thereof in a half-open position; and,

FIG. 18 is a bottom view thereof in an open position.

(Continued)

The portions of the luminaire shown in broken lines form no part of the design.
